Chas. M. Candy. Atty:

UNITED STATES PATENT OFFICE.

BERNARD D. WILLIS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MULTIOFFICE TELEPHONE SYSTEM.

Application filed September 24, 1923, Serial No. 664 374. Renewed July 23, 1927.

The present invention relates to multi-office telephone systems in general, but is concerned more particularly with multi-office telephone systems in which calls are completed through the medium of automatic switches, and the principal object is the provision of new and improved trunking arrangements for such automatic telephone systems of the above type as employ so-called "universal switchers."

This case may be considered an improvement on the co-pending application of Smith, Serial No. 550,451, filed April 7, 1922, and issued April 5, 1927, as Patent No. 1,623,320. In the Smith case, the utility for the universal switcher is set forth very completely and, although the universal switcher is adapted to be used in any one of a great number of situations encountered in large multi-office telephone systems, it has been chosen to illustrate the present invention in connection with one of the simpler cases of multi-office telephone systems in which there are not more than ten main offices and in which one or more of the main offices may have associated therewith one or more sub-offices.

It has been common practice for some time to provide sub-offices, or satellites, for the main offices, and to handle all of the calls outgoing from a sub-office through switches in the associated main office, as well as all the calls incoming to the sub-office, the sub-office containing only the switching equipment required for completing calls incoming from the main office; for extending calls to the main office; and for completing local calls.

Since it is always desirable in connection with one system to arrange the trunking system in such a manner that the number of any one line is the same regardless of from which point it is called, it is desirable that a first selector in the main office be seized and made ready for use when the receiver is removed at the calling station in the branch office. Accordingly, the aforesaid first selector in the main office is operated when the first digit is called and as the number is dialled the connection is set up step by step in the main office.

Unless special trunking arrangements were made to prevent it, a call from one sub-exchange subscriber to another subscriber

in the same sub-exchange would take up a trunk to the main office and would take another trunk from the main office back to the sub-office, thus tying up two inter-office trunks needlessly. Accordingly, the long established practice has been to provide arrangements for cutting out the inter-exchange trunks when the call is local to the originating sub-office, and, in order to accomplish this result, various trunking layouts have been proposed. For example, in the Smith case hereinbefore referred to, a universal switcher is seized when the receiver is removed, and a secondary switch associated with the universal switcher immediately thereupon seizes a trunk extending to the main exchange, and, if the call is completed through the main exchange, no further trunking operations take place in the sub-exchange. On the other hand, if the call is found to be local to the originating sub-exchange, a second secondary switch is connected up by the universal switcher; the one which seized the main exchange trunk is disconnected; and the call is completed through the local switches.

Since the trunks with which the universal switchers are associated are used not only for calls to main but also for local calls, it is very evident that the number of these trunks, in practically every case, is greater than the number of trunks extending from the sub-exchange to the main exchange. Accordingly, it is an object of the present invention to reduce the number of universal switchers required by associating the universal switchers with the trunks extending from the sub to the main exchange, instead of with the much larger group of trunks through which both main exchange calls and local sub-exchange calls are handled.

There are various other objects, having to do with the circuit details necessary to carry out the invention, which will not be mentioned here but will be explained fully hereinafter.

In addition to the Smith application referred hereinbefore, this application in certain respects may be considered an improvement on the pending application of Lomax, Serial No. 565,727, filed June 3, 1922.

Referring now to the accompanying single figure of drawing, one substation denoted by the reference character A is shown. The

associated line comprises conductors 11 and 12 terminates at the sub-exchange in the line switch C. This line switch has access to a number of trunks of which the trunk comprising conductors 31 to 34, inclusive, is one. This trunk has associated with it two secondary switches SS and SS'. The secondary switch SS has access to trunks leading to the main exchange, while the secondary switch SS' has access only to local trunks leading to selectors such as E.

There is a universal switcher, such as the universal switcher US, associated with each of the repeaters, such as the repeater R, one of which is provided for each of the trunks extending from the sub-exchange to the main exchange.

The remaining switches in the sub-exchange, as well as all the switches in the main exchange, have been eliminated from the drawings in order that the showing may be simplified.

It is thought that the invention can best be understood from a detailed description of the operation of the apparatus involved. For this purpose it will be assumed that the subscriber at substation A desires to call another subscriber, whose number is 522,689 and whose line therefore terminates in the local sub-office, it being assumed that all numbers beginning with 522 are local to the sub-office.

When the receiver is removed at substation A, line relay 15 energizes over line conductors 11 and 12 and closes a circuit for the lower winding of switching relay 14 and stepping magnet 16 in series at armature 21, and at armature 22 connects test wiper 24 to the junction of the lower winding of switching relay 14 and stepping magnet 16.

The further operation depends upon whether the trunk upon which the wipers of the line switch C are standing is busy or idle. If it is busy, the lower winding of switching relay 14 is short circuited by the ground potential encountered on test contact 28 by test wiper 24, and the wipers are advanced step by step in search of an idle trunk by the buzzer-like action of stepping magnet 16 which is operated through test wiper 24. In this case, however, it will be assumed that the trunk is idle when the call is made, in which case the lower winding of switching relay 14 is not short-circuited, and said relay energizes immediately. Stepping magnet 16 does not energize at this time on account of the high resistance of the lower winding of switching relay 14. Upon energizing, switching relay 14 disconnects test wiper 24 from the junction of its own winding and that of stepping magnet 16 and connects it to the private normal conductor 13 at armature 18, thereby preparing the holding circuit; places ground on test contact 29 through test wiper 25 at

armature 19; and at armature 17 and 20 disconnects line conductors 11 and 12 from the line relay 15 and ground and extends them by way of wipers 23 and 26, bank contacts 27 and 30, and trunk conductors 31 and 34 to armatures 48 and 51 of switching relay 45 of the secondary switch SS. As a result of the ground potential being placed on bank contact 29, a circuit is closed through the normally closed contacts controlled by armature 44 of relay 41, and the normally closed contacts controlled by armature 50 of relay 45, for line relay 46 of the secondary switch SS. Line relay 46 accordingly energizes and places ground on conductor 32 at armature 52, thereby closing the holding circuit for the upper winding of switching relay 14, through contact 28, wiper 24, and armature 18 and its working contact, before the slow acting line relay 15 has had time to deenergize.

As a further result of the energization of line relay 46, it closes a circuit for switching relay 45 and stepping magnet 47 in series at armature 53, and at armature 54 connects test wiper 56 to the junction of the winding of switching relay 45 and stepping magnet 47, thereby closing the test circuit. The secondary switch SS operates to select an idle trunk in the manner described for the line switch S. Assuming that the trunk comprising conductors 61-63, inclusive, and terminating in bank contacts 58-60, inclusive, is idle, the wipers of the switch are not moved and switching relay 45 energizes immediately, thereby switching the connection through to the said trunk. Specifically, the energization of relay 45 results in the test circuit being opened and a subsequent holding circuit for switching relay 14 of the line switch C being prepared at armature 49. Relay 45 also locks itself to the grounded conductor 33 at armature 50 and disconnects the slow acting line relay 46 therefrom, and at armatures 48 and 51 extends the trunk conductors 31 and 34 through wipers 55 and 57, bank contacts 58 and 60, trunk conductors 61 and 63, and the normally closed contacts controlled by armatures 71 and 72 to the windings of line relay 68 of the repeater R. Line relay 68 thereupon energizes over the calling line and closes a circuit for release relay 69 at armature 74. Release relay 69, upon energizing, places ground on the locking conductor 96 at armature 76; opens at armature 77 a point in the circuit of release magnet 83 of the universal switcher US and prepares a circuit for the slow acting relay 70, as well as for the stepping magnet 85 of the universal switcher US; and at armature 78 places ground on release trunk conductor 62, thereby completing a new holding circuit for the upper winding of switching relay 14 of the line switch C before the slow

acting relay 46 of the secondary switch SS has had time to deenergize.

As a further result of the above mentioned energization of line relay 68, it closes 5 a bridge across trunk conductors 97 and 98 of the trunk extending to the main exchange at armature 75. This bridge includes impedance 73, the upper winding of the electro-polarized relay 67, and the resting contact 10 of armature 79 and said armature. When this bridge is closed the selector in which the trunk terminates at the main exchange is prepared for operation in the usual manner. It will be noted that the 15 current is now flowing through both the upper and the lower windings of the electro-polarized relay 67. This relay is not operatively energized at this time, however, owing to the fact that the current flowing in 20 one winding is in opposition to the current flowing in the other winding.

The above operations have occurred in response to the removal of the receiver at the calling substation A, and the universal 25 switcher US as well as the selector associated with the repeater R and located in the main exchange are now in readiness to be operated.

When the calling device at the calling 30 substation is manipulated in accordance with the first digit 5 of the desired number, the circuit of line relay 68 of the repeater R is opened five times momentarily. Each time line relay 68 deenergizes in response to 35 one of these interruptions, it opens the bridge across trunk conductors 97 and 98 at armature 75 and at armature 74 completes the circuit of relay 70 through armature 77 and its working contact. Relay 70 energizes in response to the first closure of 40 its circuit and, being slow acting, maintains its armature attracted throughout the series of operations. Relay 70 disconnects conductor 97 from the upper talking condenser 45 and connects it directly to the working contact of armature 75 at armature 79. This is the usual expedient made use of to improve the switch control circuit during dialing.

50 As a further result of each of the deenergizations of line relay 68, a circuit is closed in multiple with the slow acting relay 70 for stepping magnet 85 of the universal switcher US, the circuit at the beginning of 55 the first impulse delivered to magnet 85 being as follows: from ground by way of armature 74 and its resting contact, armature 77 and its working contact, off normal contacts 91, slow acting relay 87, and stepping 60 magnet 85 to battery. By the operation of stepping magnet 85 the wiper 84 is advanced step by step and comes into engagement with the fifth associated bank contact. Relay 87 is energized in series with stepping 65 magnet 85 upon the first of the above men-

tioned impulses of current which are sent to the said stepping magnet and, being slow acting, retains its armature attracted throughout the series of impulses and at 70 armature 89 maintains its own circuit and that of stepping magnet 85 closed after the off normal contacts 91 have opened as they do upon the first step of the wiper 84.

At the end of the stepping movement, series relay 87 deenergizes and places 75 ground on the winding of relay 86 thereby closing a circuit through the said relay as follows: from ground by way of the resting contact and armature 97, relay 86, normally closed contacts controlled by armature 88, wiper 84, the fifth associated bank contact, normally closed contacts controlled by armature 95, and the upper winding of the two step relay 80 to battery. Relays 80 and 86 energize in series over this 80 circuit. However, owing to the copper slug which is placed on the armature end of the core of relay 86, as is denoted by the upper black portion of the core of this relay, instead of the more usual position at the heel 85 end of the core, the said relay 86 is slightly slow in energizing and accordingly relay 80 is able to energize first. Relay 80, on the other hand, is a two step relay and pulls up only part way when energized through its 90 upper winding, which is composed of a small number of turns of wire having a relatively high resistance. When relay 80 is energized through this upper winding, its contacts marked 1 close, while the ones 95 marked 2 remain unoperated. Accordingly, armature 95 is brought into engagement with its associated contact and the lower armature of the relay is brought into engagement with its associated contact. Armature 95, it may be stated, does not perform any useful function at this time from a circuit standpoint, but is provided to aid the lower armature spring in bringing the armature proper of the relay to a stop so 100 that it will not complete its stroke. The lower armature of relay 80, upon coming into engagement with its associated contact, closes a locking circuit through the lower winding of the relay. This locking circuit 105 is not effective at this time, however, owing to the fact that the lower winding is practically short circuited by the ground potential applied to the junction of the two windings through the low wound relay 86. 110

115 It will be seen from the above that since relay 80 is a two step relay and has not yet pulled all the way up, there is no danger of the circuit through the wiper 84 being opened before armature 88 of relay 86 can be 120 operated, otherwise relay 80 might energize too quickly and open the circuit of relay 86 before the latter could operate to close a locking circuit for itself.

125 When armature 88 of relay 86 comes into 130

engagement with its associated contact it closes a circuit through off normal contacts, 90 for release magnet 83 and when armature 88 is attracted still further it disconnects 5 wiper 84, thereby opening the initial circuit of the upper winding of relay 80. When this occurs, the lower winding of relay 80 is no longer short circuited and becomes energized in series with the upper 10 winding of the relay, whereupon the armature proper of the relay pulls all the way up resulting in the fifth bank contact being disconnected at the normally closed contacts controlled by armature 95, and also in the 15 second bank contact being connected up at the upper armature of the relay, thereby preparing a circuit for relay 81.

Responsive to the closure of the above mentioned circuit for release magnet 83, the 20 wiper 84 is restored to normal position, whereupon the circuit of release magnet 83 and relay 86 is opened at off normal contacts 90, and the relay and magnet deenergize.

25 Simultaneously with the above described operation of the universal switcher US, the selector in which the trunk comprising conductors 97 and 98 terminates at the main exchange is operated in the usual manner responsive to the interruptions of the bridge across the conductors 97 and 98 at armature 75. This selector switch raises its wipers to the fifth level and then selects an idle trunk in the usual manner.

30 When the calling subscriber operates his calling device in accordance with the second digit 2 in the desired number, two interruptions are produced in the outgoing trunk circuit at armature 75 of line relay 69, whereupon the selector last seized raises its 35 wipers to the second level and selects an idle trunk. The universal switcher US is again operated in the previously described manner and wiper 84 is brought into engagement with the second associated bank contact. Since the upper armature of relay 80 is 40 operated, two step relay 81 is connected up and operates in the same manner as described for the relay 80; closes its contacts marked 1 when the circuit of its upper winding is 45 closed; and operates its contacts marked 2 when wiper 84 is disconnected by relay 86. The wiper 84 is restored to normal by the 50 release magnet 83 in the usual manner.

55 It will be noted that, in this case, the upper armature of relay 81 connects the second bank contact with the upper winding of relay 82 so as to enable the relay 82 to be energized through the second contact upon 60 the next operation of the universal switcher. Accordingly a second reason for the use of a two step relay manifests itself at this time, namely—to prevent the relay 82 from being connected up to the second bank contact before the ground connection is removed

from the wiper 84. Otherwise relays 81 and 82 might operate one after the other, resulting in the premature operation of relay 82.

Responsive to the next operation of the calling device at the substation A, the circuit of line relay 68 of the repeater R is twice opened, whereupon line relay 68 de-energizes twice and interrupts the circuit across conductors 97 and 98 twice at armature 75. In response to each of these interruptions the selector to which the connection has been extended in the main exchange raises its wipers to the second level and selects an idle trunk (not shown) extending back to the originating sub-exchange. Simultaneously, the wiper 84 of the universal switcher US is advanced into engagement with the second associated bank contact and when relay 87 deenergizes a circuit is completed through relay 86, wiper 84, and the upper contacts of relays 80 and 81 for the upper winding of relay 82. Accordingly relays 82 and 86 energize in series. Relay 82, upon energizing, closes a locking circuit for itself at its lower armature, and relay 86, upon energizing, completes the usual circuit for release magnet 83, whereupon wiper 84 is again restored to its normal position. As a further result of the energization of relay 82, it connects the booster battery 93 to the release trunk conductor 62 through the resistance 92 and disconnects direct ground therefrom. The application of the booster battery 93 to the release trunk conductor 62 results in the energization of the marginally adjusted relay 41. This relay is also a two step relay and energizes only part way with the booster battery applied to its lower winding in series with the regular exchange battery.

65 As a result of the first step of the operation of relay 41, it places ground on conductor 99 at armature 44, thereby closing a circuit through the normally closed contacts controlled by relay 101 for line relay 102 of the secondary switch SS'. Relay 102 thereupon energizes, causing the secondary switch SS' to select an idle trunk in the usual and well known manner. Assuming that the trunk comprising conductors 113-115, inclusive, is idle, the wipers of the switch are not moved and switching relay 101 energizes immediately. Upon energizing, relay 101 locks itself to conductor 99 and disconnects the line relay 102 at armature 106; opens the test circuit and prepares a circuit for the upper winding of relay 41 at armature 105; and at armatures 104 and 107 extends the trunk conductors 31 and 34 through wipers 113 and 115 and armatures 132 and 135 to line relay 121 of the selector E. Line relay 121 thereupon energizes over the calling line in multiple with the line relay 68 of the repeater R and closes a circuit for release relay 122 at armature 126. Re-

lease relay 122 thereupon energizes and prepares the switch for operation at armature 128, at the same time placing ground on release trunk conductor 114 at armature 127. The placing of ground on conductor 114 results in a circuit being closed through wiper 111, armature 105 and its working contact, release trunk conductor 100, and armature 43 and its working contact for the upper winding of relay 41. Responsive to the closure of this circuit, relay 41 energizes fully; disconnects its lower winding at the normally closed contacts controlled by armature 42; connects release trunk conductor 32 with release trunk conductor 100 at the normally open contacts controlled by armature 42 so as to hold up the connection from the selector E; and at the normally closed contacts controlled by armature 44 opens the holding circuit of relay 45, whereupon relay 45 deenergizes and disconnects the associated wipers. This results in the partially set up connection extending through the repeater R and the switches at the main exchange and back over the trunk to the sub-exchange to be released in the usual and well known manner.

The connection is now switched over through the secondary switch SS' to the local selector E and the said selector E is in readiness to be operated in accordance with the next digit in the desired subscriber's number.

When the subscriber at substation A manipulates his calling device in accordance with the next digit 6 of the desired number, line relay 121 of the selector E deenergizes a corresponding number of times. Each time the line relay 121 deenergizes, it closes a circuit for the vertical magnet 138 as follows: from ground by way of the resting contact of armature 134, armature 126 and its resting contact, armature 128 and its working contact, series relay 123, and vertical magnet 138 to battery. By the operation of vertical magnet 138, the wipers 142-144, inclusive, are raised step by step until they stand opposite the sixth level of bank contacts. Relay 123 is energized in series with vertical magnet 138 and, being slow acting, maintains its armature attracted throughout the vertical movement. By the conjoint action of relay 123 and off normal contacts 141, which close upon the first vertical step, a circuit is completed through interrupter contacts 140 for stepping relay 124. Relay 124 energizes responsive to the closure of its circuit and closes a locking circuit for itself at armature 130, and at armature 131 prepares a circuit for rotary magnet 139.

At the end of the vertical movement, slow acting series relay 123 deenergizes and completes the rotary magnet circuit at armature 129, whereupon rotary magnet 139 ener-

gizes and advances the wipers into engagement with the first set of bank contacts in the level opposite which they were raised. Near the end of its stroke, rotary magnet 139 opens the circuit of stepping relay 124, whereupon relay 124 deenergizes and opens the circuit of rotary magnet 139, whereupon rotary magnet 139 deenergizes also.

The further operation depends upon whether the trunk terminating in the first set of bank contacts is busy or idle. In case it is idle, switching relay 125 energizes immediately. Assuming it to be busy, however, switching relay 125 is short circuited by the ground potential encountered on the test contact of the busy trunk by test wiper 143 and does not energize. In this case, stepping relay 124 energizes again, and again closes the circuit of rotary magnet 139 at armature 131, whereupon the switch wipers are advanced into engagement with the next set of bank contacts. This alternate operation of stepping relay 124 and rotary magnet 139, continues until an idle trunk is reached, which trunk may be assumed is the one terminating at bank contacts 145-147, inclusive. When this occurs, switching relay 125, being no longer short circuited, energizes in series with stepping relay 124; disconnects ground from armature 126 of line relay 121 at armature 134, thereby opening the circuit of release relay 122; opens the test circuit and prepares the holding circuit at armature 133; and at armatures 132 and 135 disconnects conductors 113 and 115 from the windings of line relay 121 and extends them by way of wipers 142 and 144, bank contacts 145 and 147, and the associated trunk conductors to the line relay of the associated connector switch. The line and release relays (not shown) of this connector switch now energize and the latter places ground on the associated release trunk conductor, thereby closing a holding circuit through test contact 146, and test wiper 143 for switching relay 125 as well as for the upper winding of relays 41 and 14 before the slow acting release relay 122 has had time to deenergize.

Responsive to the two remaining operations of the calling device at substation A, the connector switch is operated in the usual manner to complete the connection to the desired line and, when the subscriber at substation A hangs up his receiver after having finished the call, the connector switch removes ground from the associated release trunk conductor whereupon switching relay 125 of the selector E, relay 41 and relay 14 of the line switch C deenergize. Switching relay 125, upon deenergizing, completes a circuit for release magnet 136 at armature 134. The circuit includes armature 126 and its resting contact, armature 128 and its resting contact, and off normal contacts 137.

By the operation of release magnet 136 the wipers of the selector E are restored to normal position, whereupon the circuit of release magnet 136 is opened at off normal contacts 137. The connection is now released and the apparatus involved is ready for use in another connection.

Referring now again to the universal switchers US' associated with the repeater R, it is apparent that in case the wiper 84 lands upon an open contact responsive to the dialling of a digit which determines that the call can not be intended for the local sub-exchange, no circuit is completed for relay 86 and accordingly the release magnet 83 is not at that time operated and the wiper 84 is left standing off normal. When this happens the stepping magnet 85 can not be again operated until the connection being established is released and the repeater R is again seized. This is made possible owing to the fact that the first impulse of current to the magnet 85 must always come through the off normal contacts 91 which are opened as soon as the wiper 84 leaves its normal position, after which the circuit of stepping magnet is maintained at armature 89 of relay 87.

When a call is extended through the repeater R and is not switched through the secondary switch SS' to the sub-exchange the universal switcher US' is standing off normal until the connection is released at which time a circuit is closed through armature 74 and its resting contact of line relay 68, armature 77 and its resting contact of release relay 69, and off normal contacts 90, for release magnet 83, resulting in the release of wiper 84 in the usual manner.

It will be seen from the foregoing that the present invention provides a very economical arrangement for the switching of calls from one path to another in that the switching devices are associated with the outgoing trunks which are small in number. It will be seen further that the provision of the two step relay in connection with the universal switcher provides a very positive operation.

What is claimed is:

1. In a telephone system, a trunk, a first switch and a second switch individual to said trunk, two groups of trunks accessible to said switches, respectively, means responsive to a call over said trunk for operating said first switch to select a trunk in the associated group, and means for subsequently releasing said first switch and for causing said second switch to select an idle trunk in the associated group, the last named means being controlled from the trunk selected by said first switch, said control being exercised or not according to the called number.

2. In a telephone system, a trunk, two automatic switches individual thereto, two

groups of trunks accessible to said switches, respectively, means responsive to a call over said trunk for operating one of said switches to select a trunk in the associated group, registering means individual to the last named trunk, said registering means being operated over said last named trunk in accordance with the called number, and means controlled by said registering means for releasing the last named one of said switches and for causing the other of said switches to select an idle trunk in the associated group.

3. In a telephone system, a trunk, an automatic switch associated with said trunk, a group of trunks accessible to said switch, means responsive to a call over said first named trunk to cause the said switch to select an idle trunk in the associated group, a second automatic switch individual to the first named trunk, a switching relay, and means controlled from the trunk seized by the first named switch for energizing said switching relay to release said first named switch and to operate the second of said switches to seize an idle trunk in the associated group.

4. In a telephone system, a trunk, an automatic switch associated with said trunk, a group of trunks accessible to said switch, means responsive to a call over said trunk to cause the said switch to select an idle trunk in the associated group, a second automatic switch associated with the first named trunk, a switching relay, and means controlled from and individual to the trunk seized by the first named switch for energizing said switching relay to release said first named switch and to operate the second of said switches to seize an idle trunk in the associated group, said means being effective or not in accordance with the number called.

5. In a telephone system, a trunk line, means for extending a connection thereto from a calling line and for subsequently extending said trunk line towards a called line, and means individual to said trunk line and controlled in accordance with the called number for releasing said connection and for connecting the calling and called lines over another path.

6. In a main-exchange and branch-exchange telephone system, a trunk line in the branch exchange, means for connecting this trunk line with a calling line, a switch individual to said trunk line, a branch-to-main trunk line extending from a repeater in the branch exchange to a selector in the main exchange, means responsive to the connection of the said branch-exchange trunk line to the calling line for connecting the said branch-exchange trunk line with said branch-to-main trunk line, means in said repeater for repeating the series of impulses representing the called number over the trunk line to the main exchange to operate

- switching means including the selector on the distant end of the branch-to-main trunk line to complete the connection, a registering device in the branch exchange operated by contacts in said repeater simultaneous with the repeating of the impulses to the main exchange, a local-connection trunk line, and means controlled by said register in case the number desired is a branch exchange number for disconnecting said branch-exchange trunk line from said branch-to-main trunk line and for connecting it instead to said local trunk line whereby the branch to main trunk line through said first mentioned switch is freed for use by other subscribers and the connection is completed over the local trunk line to the desired local subscriber.
7. In an automatic telephone system, an exchange including two automatic switches, groups of trunks leading to different exchanges accessible by way of the first of said switches, trunks local to the exchange accessible by way of the second switch, means for extending a connection to the first switch, and means controlled through a trunk line seized by the first switch and effective if a telephone number local to the exchange is called for releasing the first switch and for extending a connection through the second switch.
8. In an automatic telephone system, an exchange including two automatic switches, groups of trunks leading to different exchanges accessible by way of the first of said switches, trunks local to the exchange accessible by way of the second switch, means for extending a connection to the first switch, and means controlled through and individual to the trunks accessible to the first switch and effective if a telephone number local to the exchange is called for releasing the first switch and for extending a connection through the second switch.
- 45 9. In an automatic telephone system wherein the establishment of connections is controlled by groups of digit impulses, a trunk terminating in an automatic switch and having a branch terminating in a second automatic switch, said second switch being normally unresponsive to the seizure of the trunk, means in said trunk controlled through the first mentioned automatic switch for rendering the second mentioned automatic switch responsive, groups of trunks accessible to the respective automatic switches, and means in the trunks accessible to the first mentioned automatic switch effective if certain groups of the controlling digit impulses are of certain values for controlling said first named means.
10. In a telephone system, a trunk having two branches each terminating in an automatic switch, one of which switches is normally unresponsive to the seizure of the trunk, groups of trunks accessible to the respective switches, means for setting up a connection over the other automatic switch to a trunk line in the associated group and for further extending a connection over the connected trunk lines in accordance with certain digits of a desired telephone number, means individual to said last mentioned trunk line operated under predetermined conditions for releasing the established connection, and for rendering the normally unresponsive switch responsive to digit impulses for extending a connection over the branch of the first mentioned trunk that leads to the normally unresponsive switch.
11. In a telephone system, a trunk having two branches each terminating in an automatic switch, one of which switches is normally unresponsive to the seizure of the trunk, groups of trunks accessible to the respective switches, means for setting up a connection over the other automatic switch to a trunk line in the associated group and for further extending a connection over the connected trunk lines in accordance with certain digits of a desired telephone number, means individual to said last mentioned trunk line operated in accordance with certain digits of a desired telephone number for releasing the established connection and for rendering the normally unresponsive switch responsive to digit impulses for extending a connection over the branch of the first mentioned trunk that leads to the normally unresponsive switch.
12. In a telephone system, a first automatic switch, a second automatic switch seized thereby, said two switches including talking conductors, a busy test conductor, and an auxiliary conductor, means controlled over the auxiliary conductor for applying a busy potential to the test conductor, means controlled over the talking conductors for releasing the connection between the two switches, and additional means effective under predetermined conditions for applying an increased potential to the test conductor, for also causing the release of the said automatic switches.
13. A universal switcher comprising a register responsive to a plurality of digits and a like plurality of two step relays connected to the bank contacts of said register.
- In witness whereof, I hereunto subscribe my name this 21st day of September, A. D., 1923.

BERNARD D. WILLIS.
